(57) **CLAIM**

The ornamental design for the tailored drapery tab, as shown and described.

DESCRIPTION

FIG. 1 shows the tailored drapery tab of this invention suspending the upper end of the drapery to the drapery rod, the fragmented rod and curtain and fastening element being for illustrative purposes only and forming no part of the claimed design;

FIG. 2 provides a prospective view of a tailored drapery tab of this invention;

FIG. 3 provides a front view thereof, the rear view being a mirror image thereof;

FIG. 4 is a side edge view, the opposite side view being a mirror image hereof

FIG. 5 is a top view;

FIG. 6 is a bottom view;

FIG. 7 is an end view showing the tailored drapery tab of FIG. 1 as installed the fragmented rod and curtain and fastening element being for illustrative purposes only and forming no part of the claimed design;

FIG. 8 is a modified view of a tailored drapery tab of this invention; and,

FIG. 9 is a front view of a modified tailored drapery tab of this invention.
